UNITED STATES PATENT OFFICE.

ARCHIE H. JONES, OF TONOPAH, NEVADA.

ORE-SEPARATING DEVICE.

1,826,453.

Specification of Letters Patent. Patented Dec. 30, 1919.

Application filed April 11, 1916. Serial No. 90,316.

To all whom it may concern:

Be it known that I, ARCHIE H. JONES, of Tonopah, in the county of Nye and State of Nevada, have invented certain new and useful Improvements in Ore-Separating Devices, whereof the following is a specification, reference being had to the accompanying drawings.

My invention relates to the so-called flotation type of ore separating processes, in which ore pulp is agitated in the presence of an oily reagent, and the primary object of my improvements is to accomplish the necessary agitation by mechanical and pneumatic means acting in conjunction with one another, under conditions which permit complete control of the process and which afford the maximum of economic efficiency.

Other improvements relate to convenience and stability of structure, and simplicity of the operating elements.

The accompanying drawings show a preferred embodiment of the invention, adapted to be directly driven by a superimposed electric motor, Figure I, being a view in side elevation.

Fig. II, being a vertical central section on the plane at right angles to the showing in Fig. I;

Fig. III, being a plan view with the upper portion of the casing removed;

Fig. IV, being a horizontal section on the line IV, IV, of Fig. II, and

Fig. V, being a partial view in perspective, showing certain details of one of the interior parts.

The device is conveniently supported upon an elevated open base 1, to which is secured an internally coned ring 2, to form a seat 40 for a casing 3, whose lower portion is in the form of a truncated cone, but which terminates, at its upper region, in a cylindrical extension 4, open at the top as shown in the sectional view of Fig. II. Said cylindrical extension carries a framework comprising a plurality of upwardly converging arms 5, which terminate in a flat top 6, adapted to support the casing 7, of an electric motor, or to carry driving mechanism for a 50 downwardly depending vertical shaft 10. Suitable bearings for said shaft are afforded by means of a central boss 8, projecting downward from the top 6, and by arms or spokes 9, extending inward from the arms 5. Centrally located within the casing 3, is a vertical cylinder 12, secured at its lower

end by means of lugs 13, which are preferably cast integrally with the base 1, the lower portion of the cylinder being cut away between the lugs, so as to afford openings 14, between the projections which are bolted to the lugs 13. A second frustoconical casing 15, of similar pitch to the casing 3, is secured at its lower extremity to the cylinder 12, at the level of the top of the openings 14, the dimensions of the two cones being such as to leave a substantial interspace 16, between the adjacent faces. Near the upper extremity of the cylinder 12, a spider, comprising the rings 18, and 19, and the radial arms 20, is attached respectively to the outer surface of the cylinder 12, and to the inner surface of the casing 15, so as to support and brace the upper extremity of the latter. An inclined annular diaphragm 21, of perforated metal is supported by means of said spider and covers the opening between the top of the cone 15, and the wall of the cylinder 12. Upon said perforated diaphragm an annular piece of textile fabric 22, having a comparatively close mesh, is secured so as to constitute a uniformly porous upper surface for the chamber between the cone 15 and cylinder 12. Said diaphragm and fabric 80 may be held in position by radial strips 23, arranged on top thereof, and secured to the arms 20. An inlet pipe 24, for compressed air, derived from any suitable source of power, leads into said chamber, and a pipe 90 25, for supplying ore pulp, leads into the interspace 16, between the cones 15, and 3, preferably near the bottom thereof. The lower portion of the downwardly depending shaft 10, carries two sets of propeller blades, 95 indicated respectively at 11, and 17, the upper blades being preferably of greater radial extent than the lower ones. Mounted upon the base 1, at intervals between the supports 13, are baffle plates 26 extending radially 100 inward from the wall of the cylinder 12, to a distance which just permits the blades of the propeller 17, to clear them, and extending vertically upward to a point near the level of the lower surface of the propeller blades 11.

At one side of the internal casing 3, a tapering discharge box or hopper 30, is arranged, having an outlet 31, at its lower end controlled by a valve 28, connected in the 110 usual way to a float 29, arranged at the desired level within the cylindrical extension.

4, of the outer casing. A circular launder 35, having an inclined bottom 36, leading to a spout 37, surrounds the upper portion of the said extension 4. A cylinder 38, of 5 somewhat larger diameter than the cylinder 12, is arranged concentrically therewith and extends downward a short distance below the upper edge thereof, forming an annular discharge opening just above the porous dia-

10 phragm 20, 21.

A discharge pipe 40, leads downward from the bottom of the casing 3, said pipe being normally closed during operation, but permitting the complete emptying of the apparatus when desired.

15 It will thus be seen that the organization comprises an outer casing and an inner casing arranged with an interspace between their walls, a conduit communicating with 20 such interspace, but inclosed with relation to the inner casing, and extending upward to a point above the latter, the top of the inner casing being composed of a porous medium, said parts being combined with a feed 25 pipe for ore pulp, communicating with said interspace, a supply pipe for compressed air, communicating with the chamber formed by the inner casing, and propelling means located within the conduit.

30 In the instance shown, the upper edge of the outer casing is of the same level throughout its entire periphery, so that the overflow takes place all around and hence the launder surrounds the entire periphery.

35 I do not, however, limit myself to this arrangement, because it is obvious that the region of overflow could be more limited, and the launder or other collecting device correspondingly limited to the region adjacent to that of overflow. It is also obvious 40 that the discharging device for treated gangue could be arranged otherwise than is shown, and might be automatically controlled by different means, or might be subject only to manual control.

The operation of the device is as follows:

The shaft 10, is actuated in the direction proper for upward propulsion through the conduit formed by the cylinder 12. Ore 50 pulp is admitted through the feed pipe 25, to the interspace 16, between the two cones, and, descending to the bottom, flows into the interior of the cylinder 12, through the openings 14. The oily material or other 55 flotation reagent is admitted with the pulp, or otherwise supplied. The ore pulp is agitated by the propellers, aided by the action of the baffle plates, and passes upward and overflows annularly over the upper edge 60 of the cylinder 12, falling upon the porous diaphragm 20—21, with a marked outward swirling motion. Compressed air being admitted to the interior of the conical chamber through the pipe 24, is forced in a finely 65 divided or atomized state through the po-

rous diaphragm, and passes into the emulsified pulp flowing downward upon said diaphragm, thus intensifying the emulsion and producing a zone of froth, carrying in suspension the values of the ore. The stream 70 of heavier pulp, after descending over the porous diaphragm, falls into the annular interspace 16, and reenters the upwardly moving stream due to the action of the propellers, so that any given unit of ore is repeatedly subjected to the emulsifying action. 75

As value-carrying froth accumulates at the top of the apparatus it overflows the rim of the cylindrical extension 4, and passes out 80 into the launder 35, from which it is discharged at any desired point. When the contents have attained a predetermined level, the action of the float 29, will open the outlet of the discharge box 30, and thus automatically permit the escape of gangue 85 at a rate determined by the feed and in conformity with any predetermined level of the float 29.

I thus combine in a single machine the desirable properties of mechanical and pneumatic agitation in the flotation process, the frothing action being more efficient than any which can be practically attained by mechanical agitation alone, and the result being obtained without the consumption of 90 power required for pneumatic agitation alone. The combined action permits running at a lower rate of speed than is possible with mechanical types, and owing to the very thorough emulsification of the pulp, 95 less air is required than with the pneumatic type of machine.

The swirling action upon the perforated diaphragm affords the best arrangement for treating relatively coarse material and heavy 105 sulfids, and also attains the best result in the diffusion of air or atomizing effect due to the relatively thin layer of ore pulp upon the porous diaphragm. The pulp circulation is maintained with great efficiency and 110 uniformity and can be controlled so as to subject the pulp to repeated treatment to any desired extent.

It will be noted that mechanically and functionally the machine is self-contained 115 in one unit, affording a complete circulation which can be persisted in to the desired extent without intermediate discharge or intake ports, such as are required for prolonged treatment by a series of units as 120 heretofore proposed.

The circulation is maintained in a strong, steady, continuous, substantially uniform flow, upward through the conduit 11, and returning through the conduit-means or interspace between the casings 3, and 15, without any period of quiescence or relative rest in either conduit or conduit-means.

The return conduit means extending substantially closed from the discharge edge 130

of the perforated medium to the pulp-admitting opening of the conduit 3, the flow therethrough is confined or restricted in a definite, substantially direct, unobstructed path. The free discharge of the ore pulp annularly all around the conduit 11, directly upon and over the substantially unobstructed perforated medium prolongs the swirl and so promotes aeration through the 10 perforated medium.

Having thus described my invention, I claim:

1. In a flotation apparatus, the combination of an upright conduit with means for admitting ore-pulp at its lower portion and a free annular overflow at its upper portion; an unobstructed annular perforated medium surrounding said conduit and adapted to receive the overflow directly 15 therefrom; means for mechanically agitating the ore-pulp within said conduit and discharging it with an outward swirl upon said perforated medium; and means for forcing air through said perforated medium 20 into the pulp thereon.

2. In a flotation apparatus, the combination of an upright conduit with an opening for admitting ore-pulp at its lower portion and an overflow at its upper portion; a perforated medium adapted to receive said overflow; means for forcing air through said perforated medium into the pulp thereon; restricted return conduit-means extending from the discharge edge of said perforated medium to the opening in said first 30 mentioned conduit, said conduit means being closed throughout its length; and means for maintaining a strong, continuous, uniform circulation of pulp through said conduit and conduit-means, agitating it within said conduit and discharging it with a swirling motion upon said perforated medium.

3. The combination of an outer casing having an opening at its upper extremity; an inner casing arranged with an interspace between its wall and the wall of the outer casing, said inner casing having a porous upper surface; a conduit communicating with said interspace, but closed with relation to the inner casing and leading through the same to a point above the top thereof; propelling and agitating means located within said conduit; means for supplying compressed air to the interior of the inner casing; means for supplying pulp to the interspace between the casings; and a collecting device arranged adjacent to the region of overflow at the top of the outer 50 casing.

4. The combination of an outer conical casing having an open top; an inner conical casing arranged with its wall at a distance from the wall of the outer casing to provide 55 an interspace; a cylinder axially arranged

with relation to said inner casing, said cylinder being open at its lower extremity to communicate with said interspace, but being closed with relation to the inner casing and terminating above the upper surface thereof, 70 said inner casing having an inclined upper surface comprising a porous medium; propelling and agitating means arranged within said cylinder; means for admitting pulp to said interspace; means for admitting compressed air to the interior of the inner casing; means for permitting the controlled discharge of gangue from said interspace; and means for collecting the overflow from the outer casing, substantially as 75 set forth.

5. The combination of an outer conical casing having an open top; an inner conical casing arranged with its wall at a distance from the wall of the outer casing to provide an inter-space; a cylinder axially arranged with relation to said inner casing, said cylinder being open at its lower extremity to communicate with said interspace, but being closed with relation to the inner casing and terminating above the upper surface thereof, 85 said inner casing having an inclined upper surface comprising a porous medium; an agitator propeller arranged within said cylinder and provided with suitable actuating 90 mechanism; baffle plates arranged within said cylinder in operative relation to said propeller; means for admitting pulp to said interspace; means for admitting compressed air to the interior of the inner casing; means 100 for permitting the controlled discharge of gangue from said interspace; and means for collecting the overflow from the outer casing, substantially as set forth.

6. The combination of an outer conical casing having a cylindrical upper portion open at the top; an inner conical casing arranged with its wall at a distance from the wall of the outer casing to form an interspace and having a porous upper surface 110 comprising textile material and a perforated rigid support therefor; a cylinder extending through said inner casing, said cylinder being provided with openings at its lower extremity communicating with the interspace between the casings, and extending above the top of the inner casing; propelling and agitating mechanism arranged within said cylinder; means for admitting ore pulp to said interspace; means for admitting compressed air to the interior of the inner casing; a collecting device arranged adjacent to the overflow edge of the outer casing; and controllable means for discharging gangue 115 from said interspace, substantially as set 120 forth.

7. The combination of an outer conical casing having a cylindrical upper portion open at the top, an inner conical casing arranged with its wall at a distance from the 130

wall of the outer casing to form an interspace, and having a porous top; a cylinder closed with relation to said inner casing and extending through and above the same; 5 said cylinder being provided with openings at its lower extremity communicating with the interspace between the casing; propelling and agitating mechanism arranged within said cylinder; a cylinder surrounding the upper extremity of said first mentioned cylinder and depending below the upper edge thereof, to form an annular overflow opening above the porous top of the inner casing; means for admitting ore pulp

to said interspace between the casings; 15 means for admitting compressed air to the interior of the inner casing; a collecting device arranged adjacent to the overflow edge of the outer casing; and controllable means for discharging gangue from said interspace, 20 substantially as set forth.

In testimony whereof I have hereunto signed my name at Tonopah, Nevada, this fourth day of April, 1916.

ARCHIE H. JONES.
